CLAUDE D. CARVER, OF PORT WASHINGTON, NEW YORK

WINDOW SHADE

Application filed November 8, 1929. Serial No. 405,568.

This invention relates to window shades, and more particularly to spring operated window shades.

The conventional window shade has undergone but little change in very many years. It is objectionable to the user because of the monotonous similarity of shades everywhere, and because of the rather flat and drab appearance presented by such shades when in use. It is objectionable to the manufacturer because inasmuch as there is no opportunity for the user to express individuality and choice, and inasmuch as the shade once installed ordinarily lasts indefinitely, the only market for shades is occasioned by the erection of new buildings. There is but little replacement market and practically no competition of the type based upon differences in appearance.

It is true that to overcome the foregoing objections special shades have been designed and marketed, but these ordinarily are rather complex in construction and operation, quite expensive, and not adapted for installation on the same mountings or simple mountings similar to those now commonly employed on window frames for supporting window shades.

The primary object of my invention is to overcome the various foregoing objections to the conventional window shade and to provide a shade of novel appearance which may nevertheless be manufactured and marketed economically, operated with all of the convenience of an ordinary window shade, and adapted to be hung upon standard window shade mountings. My novel shade differs from the ordinary flat shade in being plaited. The shade includes a spring operated roller which preferably may be similar to an ordinary shade roller and fitted with a round pin at one end and a rectangular pin at the other end, adapted for hanging the shade upon standard window frame mountings. A plurality of tapes extend from the bottom of the shade through slits in the successive plaits of the shade and are wound upon the shade roller, while additional means are employed for suspending the upper edge of the shade near the roller. When the shade is raised the tapes, rather than the shade fabric, are wound

up on the roller, and the shade itself is lifted by reason of the successive plaits of the shade being closed in flat formation by the pull of the tapes. The shade is preferably fitted with a shade stick at the bottom thereof, and a rod extending across the upper edge thereof, in order to keep the shade in shape.

A further object of my invention is to obviate the necessity of having a rather heavy shade stick at the bottom edge of the shade. This is particularly desirable inasmuch as the shade stick is preferably kept in flat rather than in edgewise position so that the plaits of the shade may close down upon the flat shade stick when the shade is raised. It is desirable not to place considerable bending stress upon such a shade stick, and further desirable to employ a relatively light shade stick incapable of taking the pull of the operating cord. It is also of advantage not to place any sudden pull upon the various tapes of the shade. To fulfill these objects and overcome these disadvantages is a further object of the present invention which is accomplished, generally speaking, by employing a tape for the operating cord of the shade, which tape is wound directly upon the shade roller and passes freely through the shade and shade stick. In this manner tension upon the operating cord or tape is applied directly to the shade roller and causes it to release the remaining tapes, thereby permitting the shade to be lowered by gravity.

It has already been mentioned that an important object of the present invention is to provide a shade of attractive appearance. The plaits of the shade, which never unfold entirely flat, present a slight color contrast due to the difference in lighting upon the upper and lower faces of each of the plaits of the shade, thereby presenting an appearance which is far more attractive than the flat drab appearance of the ordinary shade. The tapes extending through the plaits of the shade near the center thereof, in the opinion of some people, detract from the appearance of the shade, whereas it is generally conceded that the tapes extending near the side margins of the shade enhance the appearance of the shade. Accordingly, it is a further ob-

ject of the present invention to dispense with center tapes on the shade and to provide only marginal tapes.

One defect of the conventional shade is the operating cord hanging from the center thereof. This cord is directly in the line of vision when the shade is partially or wholly elevated, and is more or less an eyesore to people sensitive in these matters. Accordingly, one object of the present invention is to eliminate the usual shade cord, which is done by extending one of the marginal tapes of the shade below the shade stick for a considerable distance to act as an operating cord. This tape being at one side of the window is not open to the objection of a central shade cord.

A further object of my invention is to apply to such a shade the movement previously mentioned, whereby the operating tape pulls directly on the shade roller rather than on the shade, and a still further object of my invention is to make the shade adjustable so that it may be kept in proper shape in spite of any relative change in the lengths of the tapes due to stretching thereof, or a change in the attachment of the tapes to the roller. For this purpose one of the marginal tapes passes freely through the shade stick of the shade, but the shade stick is prevented from falling by a spring clip which is fixed on the tape just below the shade stick, and the position of which may be adjusted on the tape.

To the accomplishment of the foregoing and such other objects as will hereinafter appear, my invention consists in the elements and their relation one to the other as herein-after are more particularly described in the specification and sought to be defined in the claims. The specification is accompanied by drawings in which:

Fig. 1 is an illustration of a shade embodying my invention;

Fig. 2 is a detail of the roller thereof;

Fig. 3 is a detail of the operating tape thereof;

Fig. 4 is a fragmentary view of a modification; and

Fig. 5 is a fragmentary view of another modification.

Referring to the drawing, the shade comprises generally a spring operated shade roller 12, a plaited shade 14, and a plurality of tapes 16 and 18 extending from the bottom of the shade through slits 20 in the successive plaits of the shade and wound upon the roller 12. The roller 12 is preferably similar to a conventional shade roller and fitted with a round pin 22 at one end thereof, and a rectangular pin 24 at the other end thereof, to adapt the shade for hanging upon standard window frame mountings such as the mounting 26 in Fig. 2.

The roller 12 may be fitted with flanges 28 made of relatively light sheet metal and fixed

to the roller 12, but the use of these flanges is a refinement which is optional, for I have found that even with a rather narrow tape, say one-half inch in width, the shade may be successfully operated without flanges. It is, of course, preferably to employ a wider tape and flanges in order to make absolutely certain that the tapes will be lengthened or shortened equal amounts by rotation of the shade roller.

The bottom edge of the shade is preferably fitted with a shade stick 30 which is positioned flatwise rather than edgewise, so that the plaits of the shade may nest against the shade stick when the shade is raised, as is indicated in Fig. 3. The upper edge of the shade is provided with a rod 32 which is suspended in any suitable manner as by the metal loops 34 a slight distance below the shade roller 12. It is obvious from an inspection of Fig. 2 that in place of the mounting 26 a special mounting may be used having a depending portion adapted for the support of rod 32. The arrangement here disclosed is chosen by way of illustration in order to explain how the present shade may be arranged to replace the prior shades by simply hanging the new shade on the old mountings.

Tape 16 is attached to shade stick 30 at its lower end. Tape 18 is extended below shade stick 30 to form an operating cord or tape 36. This is preferably arranged to pass freely through a slot 38 in shade stick 30 so that tension upon tape 36 is transmitted directly to the shade roller 12. A clip 40 is fixed to the tape 36 just below the shade stick 30 to prevent the latter from dropping below the level of the lower end of tape 16. The clip 40 is preferably made a spring clip as is best shown in Fig. 3, or otherwise arranged so that its position along the tape 36 may be adjusted to make shade stick 30 horizontal. This adjustment may be used to counteract any unevenness which may be caused by an unequal stretch of the tapes, or from any other cause. The operating mechanism 42 of the clip 40 is preferably disposed at the rear or window side of the clip, while the front face may be suitably embossed as at 44 for decorative value and to permit of the manufacturer giving the shade suitable trademarking, a thing which cannot conveniently be done anywhere upon the usual shade.

In Fig. 4 a fragment of a shade is shown in which three tapes, 52, 54, and 56, are employed, of which the tape 54 is extended below the shade as at 58 to form an operating cord for the shade. The arrangement shown in Fig. 1 is preferred to that shown in Fig. 4 because it eliminates the center tape running through the body of the shade and the operating cord hanging in the center of the window, both of which may be thought by some to be unsightly. It may further be pointed out that by fastening the tape 54 to

the shade stick 60 as at 62, the tape 58 will act merely like an ordinary shade cord, whereas by eliminating the fastening means 62 and permitting the tape 58 to extend freely through a slot in shade stick 60, the tension on the tape 58 may be transmitted directly to the shade roller.

In Fig. 5 there is shown a fragment of a shade employing only marginal tapes 64 and 66, thereby eliminating the center tape in the body of the shade, but retaining the usual center operating cord 68. This arrangement necessitates that the shade stick 70, even though positioned in a flat or horizontal position, must be sufficiently strong to take the pull of the operating cord 68. This construction is quite possible and practical, but is less to be preferred than the arrangement shown in Fig. 1 in which there is no shade cord at the center of the shade and no direct bending stress is placed upon the shade stick.

The construction and operation of shades embodying features of the present invention will, for the most part, be apparent from the foregoing description thereof. It will also be obvious that the resulting shade possesses a novel and attractive appearance entirely dissimilar to that of the ordinary, and yet the operation of the shade is as simple as that of the ordinary shade, and the shade may be hung upon standard mountings without necessitating special pulley systems and operating cords running around the window frame, and similar devices.

It will be apparent that while I have shown and described my invention in the preferred forms, many changes and modifications may be made in the structures disclosed without departing from the spirit of the invention, defined in the following claims.

I claim:

1. A window shade comprising a spring operated roller, a plaited shade, a plurality of tapes extending from the bottom of the shade through slits in the successive plaits of the shade and wound upon said roller, and means supporting the upper edge of the shade near the roller.

2. A window shade comprising a spring operated shade roller fitted with a round pin at one end and a rectangular pin at the other end adapted for hanging the shade upon standard window-frame mountings, a plaited shade, a plurality of tapes extending from the bottom of the shade through slits in the successive plaits of the shade and wound upon said shade roller, and means supporting the upper edge of the shade near the shade roller.

3. A window shade comprising a spring operated shade roller fitted with a round pin at one end and a rectangular pin at the other end adapted for hanging the shade upon standard window frame mountings, a plaited

shade, a shade stick at the bottom of the shade, a plurality of tapes extending from the shade stick through slits in the successive plaits of the shade and wound upon said shade roller, and means suspending the upper edge of the shade slightly below the shade roller.

4. A window shade comprising a spring operated shade roller fitted with a round pin at one end and a rectangular pin at the other end adapted for hanging the shade upon standard window frame mountings, a plaited shade, a shade stick at the bottom of the shade, a plurality of tapes extending from the shade stick through slits in the successive plaits of the shade and wound upon said shade roller, a rod extending across and attached to the upper edge of the shade, and means supporting said rod at a point below the shade roller.

5. A window shade comprising a spring operated roller, a plaited shade, a horizontal shade stick at the bottom of the shade, a plurality of tapes extending from the shade stick upwardly through slits in the successive plaits of the shade and wound upon the roller, one of said tapes extending below the shade stick for a considerable distance to act as an operating cord, a rod extending across and attached to the upper edge of the shade, and means supporting said rod at a point near the shade roller.

6. A window shade comprising a spring operated roller, a plaited shade, a horizontal shade stick at the bottom of the shade, a plurality of tapes extending from the shade stick upwardly through slits in the successive plaits of the shade and wound upon the shade roller, one of said tapes extending downwardly for a considerable distance below said stick to act as an operating cord and passing freely through a slot in the shade stick so that tension on the tape is applied directly to the roller, and means supporting the upper edge of said shade near the shade roller.

7. A window shade comprising a spring operated roller, a plaited shade, a shade stick at the bottom of the shade, a pair of tapes extending from the shade stick near the ends thereof upwardly through slits in the successive plaits of the shade and wound upon the shade roller, one of said tapes extending below the shade stick near one side of the shade for a considerable distance to act as an operating cord, a rod extending across the upper edge of the shade, and means supporting said rod at a point near the shade roller.

8. A window shade comprising a spring operated roller, a plaited shade, a horizontal shade stick at the bottom of the shade, a pair of tapes extending from the shade stick near the ends thereof upwardly through slits in the successive plaits of the shade and wound upon the shade roller, one of said tapes extending through a slot in the shade

stick for a considerable distance to act as an operating cord, means fixed to the latter tape just beneath the shade stick to hold the stick in horizontal position, and means supporting the upper edge of said shade near the shade roller.

9. A window shade comprising a spring operated roller, a plaited shade, a horizontal shade stick at the bottom of the shade, a pair of tapes extending from the shade stick near the ends thereof upwardly through slits in the successive plaits of the shade and wound upon the shade roller, one of said tapes extending through a slot in the shade stick for a considerable distance to act as an operating cord, an adjustable clip fixed to the latter tape just beneath the shade stick to hold the latter in horizontal position, and means supporting the upper edge of said shade near the shade roller.

10. A window shade comprising a spring operated shade roller fitted with a round pin at one end and a rectangular pin at the other end adapted for hanging the shade upon standard window-frame mountings, a plaited shade, a horizontal shade stick at the bottom of the shade, a pair of tapes extending from the shade stick near the ends thereof upwardly through slits in the successive plaits of the shade and wound upon the shade roller, one of said tapes extending through a slot in the shade stick for a considerable distance to act as an operating cord, an adjustable clip fixed to the latter tape just beneath the shade stick to hold the latter in horizontal position, a rod extending across the upper edge of the shade, and means supporting said rod at a point below the shade roller.

Signed at New York in the county of New York and State of New York this 4th day of November, A. D. 1929.
